UNITED STATES PATENT OFFICE.

FRANK J. KAUFMAN, OF COLUMBUS, OHIO, ASSIGNOR TO NATIONAL BINDING MACHINE COMPANY, A CORPORATION OF NEW YORK.

WORK-HOLDER FOR THE SEALING OF CARTONS.

1,269,821.

Specification of Letters Patent. Patented June 18, 1918.

Application filed June 10, 1914. Serial No. 844,141.

To all whom it may concern:

Be it known that I, FRANK J. KAUFMAN, a citizen of the United States, and a resident of the city of Columbus, county of Franklin, 5 and State of Ohio, have invented an Improvement in Work-Holders for the Sealing of Cartons, of which the following description, in connection with the accompanying drawings, is a specification, like letters on 10 the drawings representing like parts.

The present invention relates to a work holder comprising a stand or form, to be used in connection with the sealing of fiber cartons or the like, and consisting in the 15 provision of suitable adjustable means for holding the box or carton during the sealing operation, the whole being so constructed that one stand with adjustable or interchangeable tops may be used in the sealing 20 of several different sized cartons, thus obviating the necessity, heretofore existing, of a separate complete sealing form for each size of carton sealed.

Numerous machines have been developed 25 for moistening and delivering gummed tape for the sealing of cartons which, operated either mechanically or by hand, will deliver strips moistened and ready to be applied to the cartons. The application of these strips 30 to the cartons has however, been seriously hindered by the lack of suitable means for holding the carton during the sealing operation. This is especially true of that portion 35 of the operation of sealing which is termed in the trade "making up" the cartons, *i. e.*, preparing them for packing with the goods to be shipped therein. To facilitate this portion of the operation, thereby shortening 40 the time and minimizing the labor heretofore required, the present device has been constructed. A further object of the present invention is to provide a stand or form of such improved construction that the equipment required for making up many different 45 sizes of boxes is simplified and materially reduced.

It has been suggested heretofore that a form consisting of a stand and a top of such size that it will fit into the box to be sealed 50 be provided, over which the box may be made up ready to receive whatever is to be packed therein. Where several different sizes of cartons were used, as many different stands were required. The present invention 55 contemplates the use of one stand or support

in connection with different sizes of tops which may be removably attached to the stand in any convenient manner.

The present invention will be readily understood in connection with the accompanying 60 drawings, in which,

Figure 1 is an end elevation of the stand member;

Fig. 2 is a front elevation of the stand member;

Fig. 3 is a plan of three interchangeable 65 top pieces, the means of attaching the same to the stand being shown thereon;

Figs. 4 and 5 are detail views of means for securing an adjustable stop to the stand; 70

Fig. 6 is a perspective of the stand as it would be used in relation to the bench upon 75 which are mounted a gummed tape delivering machine and a supply of liquid adhesive, 75 a carton being shown in outline upon the form.

Referring to Fig. 1 of the drawings, the stand is seen to comprise two upright members *a* and *b*, suitably braced and connected 80 at the top. Means are provided on the top of the stand by which interchangeable top pieces, hereinafter referred to, may be secured thereto, the attaching means being herein shown as a cleat *c*. Vertical slots *d* 85 and *e* are provided in the end pieces *a* and *b* of the stand and an adjustable stop or cross-bar *f* is provided to pass through these slots. This cross-bar may be adjusted in any desired position with relation to the top of 90 the stand in order to hold the carton on the stand in proper relation to the top thereof, as will appear from Fig. 5 of the drawings. Interchangeable heads or top members, *g*, *h*, and *i* of any desired size, the size being determined by the size of the cartons to be sealed, are provided as shown in Fig. 3. Each interchangeable top piece is provided with means of attachment corresponding to the means of attachment on the stand, the 95 means being shown herein as a cleat *j* adapted to interlock with the cleat *c* on the top of the stand. It is contemplated that attaching means other than those shown herein may be employed, the object being to provide means whereby the tops may be quickly secured to and removed from the stand at the same time giving a firm connection between these parts.

In order to make the stop or cross-bar *f* adjustable in the slots *d* and *e* in the ends *a* 110

and *b* of the stand, each slot is equipped on one side with a series of notches *k* and the cross bar at the point where it passes through these slots is provided with a series 5 of teeth *l* to engage the notches *k*. To insure firm engagement with the notches, a spring lever mechanism is provided on the cross-bar at a point opposite the teeth. This mechanism is shown herein as a lever *m* pivoted at *n* and pressed against the smooth 10 side of the slot by a coiled spring *o*. Obviously other means may be employed for making this cross-bar adjustable with relation to the top of the stand. In order to adjust 15 just the cross-bar the operator grasps the bar and by pressing the lever *m* toward the bar releases the teeth *l* from engagement with the notches *k*. The bar may then be moved up or down in the slots *c* and *d* as 20 desired and upon releasing the lever the teeth will again firmly engage the notches. When a carton is being made up over the 25 form, this cross-bar, having been adjusted to the first carton of a number of the same size to be sealed, acts as a stop upon which rest the flaps of the open end of the carton; thus automatically positioning the carton for the operation of sealing, all as will appear from Fig. 6 of the drawings.

30 Fiber cartons are usually collapsed when delivered to the users and to prepare these cartons to be packed with goods for shipment they must be expanded and made up, as it is termed. The operation of making 35 up the cartons when the present invention is used in connection therewith consists in first selecting one of the interchangeable tops which will fit inside the carton. This top is placed on the stand and secured there- 40 to by means of the interlocking cleats. The stand is positioned adjacent a bench upon which is mounted a gummed tape machine and a supply of liquid adhesive. The expanded carton blank is slipped down over 45 the form and the stop or cross-bar adjusted so that the flaps of the open end will rest thereon. Upon making up subsequent cartons of the same size this cross piece will automatically position the carton upon the 50 form. The flaps of the box or carton which will constitute the bottom thereof, are then folded inwardly and liquid adhesive is applied between the inner and outer flaps which are thereupon pressed firmly together. 55 Strips of tape of such length that they will extend across the box and overlap the edges to a certain predetermined extent are then drawn from the gummed tape machine and pasted crosswise of the box at the 60 ends and in the center. Another strip of tape of sufficient length is drawn from the machine and applied over the center seam formed by the side flaps, this strip likewise extending down the sides of the box as de- 65 sired. This operation of sealing will be

readily understood by referring to Fig. 6 of the drawings, wherein a box *p* is shown in outline on the form and a sealing machine *q* is shown on a bench *r* adjacent to the sealing form. When the bottom of the box 70 is thus made up the carton is removed from the form and is ready to be packed for shipment. The sealing of the top of the carton after packing may be accomplished in the usual manner. 75

It is apparent from the foregoing description that the present invention consisting, as it does, of adjustable means for holding cartons to be sealed or made up, will be of value in overcoming certain difficulties heretofore existing in this art by first, providing means for holding the carton and second, by making such means adjustable to accommodate cartons of varying sizes. 80

I claim as my invention: 85

1. The combination to form a complete sealing and work-holding device for fiber cartons, of a bench for supporting the sealing materials, a stand for holding substantially on a level therewith and adjacent thereto, the fiber cartons to be sealed, said stand having a flanged cleat and a set of interchangeable heads adapted to fit on the top of the stand for the purpose of supporting and presenting to the bench cartons of 95 different sizes for sealing, each of said heads being provided with a pair of flanged cleats adapted to engage the flanged cleat mounted on the stand, a blank positioning bar slidably mounted in said stand and underlying said flanged cleat, and a yielding bar locking member adapted to hold said bar in any desired operative position. 100

2. The combination to form a complete sealing and work-holding device for fiber 105 cartons, of a bench for supporting the sealing materials, a stand for holding substantially on a level therewith and adjacent thereto, the fiber cartons to be sealed, said stand having a flanged cleat, a set of interchangeable heads adapted to fit on the top 110 of the stand for the purpose of supporting and presenting to the bench cartons of different sizes for sealing, each of said heads being provided with a pair of flanged cleats 115 adapted to engage the flanged cleat mounted on the stand, means provided on said stand to position the carton blanks in a predetermined relation for making up the bottom of the carton, said means being adjustable to adapt it for cartons of different sizes, and yielding means for securing said blank positioning means in any desired operative position. 120

3. The combination of a stand for holding cartons, said stand having a flanged cleat, and a set of interchangeable heads adapted to fit on the top of the stand for the purpose of supporting cartons of different sizes, each of said heads being provided 125

130

with a pair of flanged cleats adapted to engage the flanged cleat mounted on the stand, a blank positioning bar slidably mounted on said stand and underlying said flanged cleat, and a yielding bar locking member adapted to hold said bar in any desired operative position.

4. The combination of a stand for holding cartons, said stand having a flanged cleat, a set of interchangeable heads adapted to fit on the top of the stand for the purpose of supporting cartons of different sizes, each of said heads being provided with a pair of flanged cleats adapted to engage the flanged cleat mounted on the stand,

means provided on said stand to position the carton blanks in a predetermined relation for making up the bottom of the carton, said means being adjustable to adapt it for cartons of different sizes, and yielding means for securing said blank positioning means in any desired operative position. 20

In testimony whereof, I have signed my name to this specification, in the presence of two subscribing witnesses.

FRANK J. KAUFMAN.
